Attorney

UNITED STATES PATENT OFFICE.

CHARLES O. ANDERSON, OF OMAHA, NEBRASKA.

ADJUSTING MEANS FOR RAILWAY BRAKES.

Application filed May 12, 1924. Serial No. 712,774.

To all whom it may concern:

Be it known that I, CHARLES O. ANDERSON, a citizen of the United States, residing at Omaha, in the county of Douglas and State of Nebraska, have invented certain new and useful Improvements in Adjusting Means for Railway Brakes, of which the following is a specification.

My invention relates to manual adjusting means for railway brakes, and it is the object thereof to provide simple means which may be added to the present standard brake equipment, to enable closer or more accurate adjustment of the slack or clearance between the brake-shoes and wheels when the brakes are in released position, whereby to secure more uniform travel of the air-brake-piston in the application of the brakes, with a corresponding uniformity of cylinder-pressure and braking-pressure.

Constructions embodying my invention are illustrated in the accompanying drawings, in which Fig. 1 is a longitudinal vertical section, partly diagrammatic, of a car-truck having my adjusting means applied to the brake-rigging thereof, Fig. 2 is a detail side view of the dead-lever-guide and upper end of the dead-lever, showing one manner in which my adjusting means may be applied in practice, Fig. 3 is a plan view of the same, Fig. 4 is a detail side view of the detachable head for the dead-lever, Fig. 5 is a section on the line 5—5 of Fig. 4, Fig. 6 is a side view of the upper portion of the dead-lever, Fig. 7 is an end view of a slightly different form of the detachable head for the dead-lever, Fig. 8 is a side view of the same, and Fig. 9 is a detail plan view of the dead-lever-guide and dead-lever with integral head, as employed in the structure shown in Fig. 1.

Referring to Fig. 1, there are represented portions of an ordinary or standard brake-rigging as applied to trucks of freight cars, the principal members indicated in the figure being the wheels 10, the side-frame 11, a portion of the bolster 12, the brake-shoes 13, brake-beams 14 and 15, beam-hangers 16, the brake-rod 17 by tension of which the brakes are applied, the live-lever 18, the dead-lever 19, and the bottom-rod 20 which connects the lower ends of the live-lever and dead-lever. All of the foregoing parts will be understood to be of ordinary construction and to operate in the usual

manner. In the customary construction, the upper end of the dead-lever is pivotally connected or fulcrumed to a dead-lever-guide which is carried upon the bolster, 60 said guide having therein a series of holes through which the fulcrum-pin may be passed to connect the lever with the guide in adjusted relations suited to the state of wear of the brake-shoes.

In the construction shown in Figs. 1 and 9 the dead-lever guide 21 is substantially of the usual form, the end of said guide being pivotally connected with a lug 22 on the bolster, and the guide being curved to 70 conform approximately with an arc described about the axis of the connection between the dead-lever and the respective brake-beam. The guide is formed from a flat bar which is doubled to form parallel 75 sides, the same being spaced apart sufficiently to receive the end of the dead-lever between them. In said parallel sides of the guide there are the usual series of holes 23 for the fulcrum-pin 24, said holes being uniformly spaced longitudinally of the guide. It will be obvious that as the minimum distance between the successive holes 23 must be greater than the diameter of the fulcrum-pin, and the diameter of said pin must be such as to have the required 80 strength, the changing of the lever-fulcrum from one of the holes to another will effect a relatively large variation of the brake-shoe-clearance. In actual practice, the center-to-center spacing of the holes in the dead-lever-guide is usually 1½ inches, the diameter of the fulcrum-pin is 1 inch, and the variation of braking-pressure resulting 85 from increased or decreased piston-travel of the air-brakes, is undesirably great when the dead-lever fulcrum is changed from one hole to the next on the guide. This result is obviated in my improved construction by 90 providing upon the upper end of the dead-lever an elongated head having therein a plurality of holes, spaced differently from the holes in the guide, so that pairs of the holes in said head and the guide will be brought into register successively by 95 variations in the relation of the lever and guide less in extent than the distance between successive holes in the guide. In the structure represented in Figs. 1 and 9, the head 25 is formed integrally with the upper end of the dead-lever, and there is 100 provided in said head three holes of which 105

the spacing is greater by one-third than the spacing of the holes in the guide. For example, if the spacing of holes in the guide is $1\frac{1}{2}$ inches, the spacing of the holes in the head should be two inches, if three holes are provided in the head. Referring to Fig. 1, it may be seen that if the fulcrum-pin 24 be withdrawn and the dead-lever moved, relatively to the guide, one-third of the distance between the centers of the holes in the guide, another pair of holes in the lever and guide will come into register, so that the fulcrum-pin may be inserted therein. Thus a much more accurate adjustment of the brake-shoe clearance may be effected than is possible by the usual means provided for connecting the dead-lever and the guide. Any desired number of holes may be provided in the head of the dead-lever, the spacing of said holes being in such proportion to the spacing of the holes in the guide as to successively come into register with the latter by uniform variations in the relation of the lever and guide.

Instead of the head formed integrally with the dead-lever, a separate or detachable head may be employed, such head being secured upon the end of the ordinary dead-lever. In the structure represented in Figs. 2 to 6, inclusive, the head 35 is formed with a central socket or recess into which the upper end of the dead-lever fits, the fulcrum-pin-hole 34 in the lever being in register with the central hole 33 in the head. Lugs 36 extend from the head at the sides of the lever, and a bolt or rivet 37, passing through registering holes in said lugs and the lever, fixedly secures said parts together. With the head 35 it is necessary to employ a special guide 31, of which the sides are spaced apart sufficiently to receive between them both the head and lever, instead of being spaced to receive only the lever.

In Figs. 8 and 9 is represented another form of separate or detachable head for the dead-lever, said head being adapted for use with the ordinary guide 21 in which the sides are spaced only far enough apart to receive the end of the lever between them. Said head has side portions 45 which straddle over the outer sides of the guide, the guide lying between said side-portions as indicated by dotted lines in Fig. 7, and beneath the guide is a socket-portion 46 which fits upon the upper portion of the

lever and is fixedly secured thereto by bolts or rivets passed through holes 47 in said socket-portion.

Where my invention is to be supplied for brake equipment now in use, the simplest way in which the change can be made is to place upon the dead-levers the heads of the last-described form, and to supply fulcrum-pins of the extra length required to pass through the spaced sides 45 of said heads. By this means the improved adjusting means may be provided without change of the dead-lever-guides, or of the dead-levers except to form in said levers the holes to correspond with the holes 47 in the heads.

In general, it is preferable to provide upon the dead-levers the integral T-heads 25, as first described and as shown in Figs. 1 and 9.

Now, having described my invention, what I claim and desire to secure by Letters Patent is:

1. Railway-brake adjusting means, comprising, in combination, a dead-lever-guide having a series of longitudinally spaced fulcrum-pin holes, a dead-lever, an elongated head on said dead-lever adjoining said guide, said head having a plurality of fulcrum-pin holes spaced differently from the holes in the guide, and adapted to register successively with the holes in the guide by relative movement of the lever and guide less than the distance between successive holes in the guide.

2. In a railway brake mechanism, the combination with a dead-lever; and a dead-lever-guide having a series of longitudinally spaced fulcrum-pin holes therein, of a head carried by said lever adjoining said guide, said head having a plurality of fulcrum-pin holes spaced in vernier-like relation to the holes in the guide, whereby the holes in the head may register successively with holes in the guide when the lever is at adjusted positions intermediate those in which any one hole of the head is in register with a hole in the guide, and a fulcrum-pin insertible through the registering holes to connect the lever and guide in said intermediate positions of adjustment.

3. A structure as set forth in claim 2, in which the head is formed separately from the body of the dead-lever and is provided with a socket for receiving the end of said lever, and means for fixedly connecting the head and lever.

CHARLES O. ANDERSON.
